US00D821245S

(12) **United States Design Patent** (10) Patent No.: **US D821,245 S**
(45) Date of Patent: ** *Jun. 26, 2018

(54) **BAND FOR A WEARABLE FITNESS BAND SYSTEM**

(71) Applicant: **Fitbit, Inc.**, San Francisco, CA (US)

(72) Inventors: **Timothy Scott Lowe**, Newark, CA (US); **Gad Amit**, San Mateo, CA (US); **Daniel Joseph Clifton**, San Francisco, CA (US); **Erik Keith Askin**, San Francisco, CA (US); **Susan Elizabeth McKinney**, San Francisco, CA (US); **Jessica Sheung-yan Ng**, San Francisco, CA (US); **Simon Andrew Quay**, Portland, OR (US); **Parker Allen Drennan**, San Jose, CA (US)

(73) Assignee: **Fitbit, Inc.**, San Francisco, CA (US)

(*) Notice: This patent is subject to a terminal disclaimer.

(**) Term: **15 Years**

(21) Appl. No.: **29/563,192**

(22) Filed: **May 3, 2016**

CLAIM

We claim the ornamental design for a band for a wearable
fitness band system, as shown and described.

DESCRIPTION

FIG. 1 is an isometric view of a band for a wearable fitness
band system shown in an environment of use.

FIG. 2 is a front view of a first band portion of the band for
a wearable fitness band system of FIG. 1.

FIG. 3 is a rear view thereof.

FIG. 4 is a side view thereof; the opposing side view being
a mirror image.

FIG. 5 is a top view thereof.

FIG. 6 is a bottom view thereof.

FIG. 7 corresponds with FIG. 3 but is shown with a broken
dash-dot-dash line to indicate the plane upon which the
sectional view shown in FIG. 8 is taken from.

FIG. 8 is a cross-sectional view taken along line 8-8 of FIG.
7.

FIG. 9 is a rear view of a second band portion of the band
for a wearable fitness band system of FIG. 1.

FIG. 10 is a front view thereof.

FIG. 11 is a side view thereof; the opposing side view being
a mirror image.

FIG. 12 is a top view thereof.

FIG. 13 is a bottom view thereof.

FIG. 14 is an off-angle view thereof; and,

FIG. 15 is an off-angle view of the first band portion of FIG.
1.

Stipple shading has been used to convey surface contours
and does not indicate texture. The broken lines used to show
a case portion in FIG. 1 illustrate environmental structure
and form no part of the claimed design. The broken lines
used to illustrate the ends of the first portion and the second
portion of the band in FIGS. 1-14 and the receptacles of the
first portion and the second portion shown as abutting the
case portion in FIG. 1 form no part of the claimed design.
